UNITED STATES PATENT OFFICE.

RETURN B. SWAIN, OF PHILADELPHIA, PENNSYLVANIA.

RAISING AND FORMING MACHINE FOR METALLIC PLATE-WORK.

SPECIFICATION forming part of Letters Patent No. 440,888, dated November 18, 1890.

Application filed May 1, 1890. Serial No. 350,231. (No model.)

To all whom it may concern:

Be it known that I, RETURN B. SWAIN, a citizen of the United States, residing at Philadelphia, in the county of Philadelphia and State of Pennsylvania, have invented certain new and useful Improvements in Raising and Forming Machines for Metallic-Plate Work; and I do hereby declare the following to be a sufficiently full, clear, and exact description thereof as to enable others skilled in the art to make and use the said invention.

This invention relates to machines for raising and forming vessels from plates of ductile metal, and has for its object the facilitating of such work by relieving the workmen of the labor of hammering, and by expeditiously changing the dies as the raising of the work progresses; and to this end it consists in a combination of a power-actuated hammer with a mechanism for successively bringing each of the series of dies under the hammer, as is shown in the drawings annexed, and fully described in this specification.

Referring to the drawings, Figure 1 shows a side elevation of this invention. Fig. 2 shows a front elevation thereof, and Fig. 3 shows a plan thereof.

The same reference - marks indicate like parts in the several figures.

A represents the hammer reciprocated vertically in guides A' and A² by means of a lever B, pivotally attached to its upper end, which lever B is pivoted to a vibrating fulcrum B³, and receives reciprocating motion from a connecting-rod C, pivotally attached to the lever B by a clutch, adjustable lengthwise on the rod C from the connected crank C' in a shaft C², driven by a pulley D and belt B', tightened by a riding pulley B², supported and turning upon an arm D⁷ of the treadle-lever D³, pressed against the belt D by the downward motion to a treadle-lever D⁸. An arm D⁴ of the treadle D³ presses the brake-shoe D⁶ against the balance-wheel C⁶ on the shaft C² by the reaction of the spring D⁵, attached to the treadle-lever D³.

Supported on the frame of the machine and located under the hammer A is a table E, susceptible of a gradual intermittent rota-

tion upon its central vertical axis. In this table E are secured dies or molds E' E² E³ E⁴, &c., having different degrees of concavity and also a flat surface E⁷ for planishing. This table E may be turned by the hand of the attendant, but is preferably rotated by a pawl F and ratchet F' and held by a latch or stop F², arranged to engage in notches F³ in the table E, so located in relation to the several dies E' E² E³ E⁴, &c., and this flat surface E⁷ as to hold them successively under the hammer A. The several dies E' E² E³ E⁴, &c., are successively of greater depth or of shorter radii of concavity.

The manner of using this machine is as follows: The workman places the flat plate of ductile metal upon the die E', and by his foot, depressing the treadle-lever D³, tightens the band D' by the pressure of the riding-pulley D² thereon, and thus causes the shaft C² to revolve with greater or less rapidity, according to the pressure exerted upon the band by the pulley D'. The crank C' and connecting-rod C impart a reciprocating motion to the lever D, which reciprocates the hammer A vertically with more or less force, according to the speed. The workman moves the plate under the hammer until it assumes the form of the die E'. He next moves the table around, so as to bring the die E² under the hammer, and the plate of metal is subjected to its action. This operation is repeated with the several dies in succession until the metal has assumed the desired depth of form. The flat portions of the article are planished on the face G by the hammer A.

By means of this machine work can be raised more rapidly than by hand and with much less fatigue to the workman.

Having described my invention, what I claim is—

1. The hammer A, reciprocated by the lever B and crank C', in combination with a series of dies E' E² E³ E⁴, secured to the intermittently-rotating table and arranged to operate substantially as set forth.

2. The hammer A, reciprocated by the lever B and crank C', in combination with the dies E', E², and E³, and planishing-surface G,

secured to the intermittently-rotating table, and arranged, as shown, to operate as set forth.

3. The guided hammer A, reciprocated by 5 the lever B, rod C, crank C', and counterbalanced wheel C³, in combination with the treadle-lever D³, arm D⁴, spring D⁵, and brake-

shoe D⁶, arranged and constructed as shown for varying the speed and force of blows, substantially as set forth.

RETURN B. SWAIN.
